MEASUREMENT OF CONVERSION CONDUCTANCE

Komnenus M. Soukaras, Washington, D. C.

Application April 26, 1939, Serial No. 270,265

2 Claims. (Cl. 250—27)

(Granted under the act of March 3, 1883, as amended April 30, 1928; 370 O. G. 757)

This invention relates to the measurement of conversion conductance of a frequency converter vacuum tube, and more particularly, to the measurement of that quantity at power frequencies.

5 Among the several objects of this invention are:

To provide simple and accurate means for measuring, at usual power frequencies, the conversion conductance of a converter or mixer tube;

10 To eliminate the complications involved in determining conversion conductance at radio frequencies or by mathematical calculation from static characteristics.

15 Other objects will appear when the following description is read in connection with the drawing wherein:

Fig. 1 is a general schematic diagram of a frequency converter tube and the immediately associated circuits;

20 Fig. 2 depicts a circuit embodying the present invention.

Conversion conductance is defined by the Standards Committee of the Institute of Radio Engineers as "the quotient of the magnitude 25 of a single beat-frequency component (f_1+f_2) or (f_1-f_2) of the output-electrode current by the magnitude of the control-electrode voltage of frequency f_1 , under the conditions that all electrode voltages and the magnitude of the electrode 30 alternating voltage f_2 remain constant and that no impedance at the frequency f_1 or f_2 is present in the output circuit. As most precisely used, the term refers to an infinitesimal magnitude 35 of the voltage of frequency f_1 ."

Conversion conductance may be obtained 40 mathematically from the static characteristics, or at radio frequencies. The first method requires elaborate mathematical treatment, and the second method elaborate apparatus. Both methods are time consuming.

In what follows will be described a simplified method for measuring conversion conductance at power frequencies by means of a separately excited milliammeter of the dynamometer type.

45 Consider a frequency converter tube of the type shown in Fig. 1. Let two sinusoidal voltages of frequencies f_1 and f_2 , respectively, be applied to the signal and oscillator grids as shown.

50 Let

$e_1 = E_1 \sin \omega_1 t$
= signal instantaneous voltage

$e_2 = E_2 \sin \omega_2 t$
= local oscillator instantaneous voltage

55 $f_1 = \frac{\omega_1}{2\pi}$, signal frequency

$f_2 = \frac{\omega_2}{2\pi}$, oscillator frequency.

Also, let $E_1 \ll E_2$.

60 The signal frequency wave may be represented

as modulating the local frequency wave. For an amplitude modulated wave we have the following well known relationship:

$$\begin{aligned} e &= E_2(1+m \cos \omega_1 t) \cos \omega_2 t & 5 \\ &= E_2 \cos \omega_2 t + \frac{m E_2}{2} \cos (\omega_1 - \omega_2) t \\ &\quad + \frac{m E_2}{2} \cos (\omega_1 + \omega_2) t & 10 \end{aligned}$$

where

$$m = \frac{E_1}{E_2} \times 100$$

15 m is the degree of modulation in percent, E_1 is the amplitude or peak value of the signal or modulating voltage, and E_2 the amplitude of the local oscillator voltage considered as the carrier.

20 From Equation 1 it is evident that the intermediate frequency voltage is simply

$$E_{i.f.} = \frac{m}{2} E_2 & 20$$

Let the electrical connection from the plate of the converter tube reach the cathode without 25 going through any impedance load. Then in terms of currents, instead of voltages, Equation 2 may be written as

$$I_{i.f.} = \frac{m}{2} I_2 & 30$$

Now, the conversion conductance is defined as

$$S_c = \frac{I_{i.f.}}{E_1} & 35$$

where again, E_1 is the peak value of the control signal voltage, and $I_{i.f.}$ is also an amplitude or peak value.

Substituting (3) in (4) we have,

$$S_c = \frac{m}{2} \frac{I_2}{E_1} & 40$$

If $E_1 \ll E_2$, it is evident that

$$m = \frac{E_1}{E_2} = \frac{\Delta E_2}{E_2} & 45$$

In terms of currents we have

$$m = \frac{\Delta I_2}{I_2} & 50$$

Substituting (6) in (5)

$$\begin{aligned} S_c &= \frac{1}{2} \left(\frac{\Delta I_2}{I_2} \right) \left(\frac{I_2}{E_1} \right) \\ &= \frac{1}{2} \frac{\Delta I_2}{E_1} & 55 \end{aligned}$$

Equation 7 is the equation for conversion conductance when both E_1 and E_2 are acting together. However, if we make E_1 , the amplitude of the control signal voltage, zero, and compen- 60

sate for it by a variation of the control signal grid bias, that is by

$$\Delta E_{c_1}$$

the validity of the resulting equation is not impaired.

We have finally,

$$S_c = \frac{1}{2} \frac{\Delta I_2}{\Delta E_{c_1}}$$

10 E_{c_1} is a direct voltage, and in order to keep constantly in mind the fact that I_2 is a peak value, we write the above equation in the following final form:

$$15 S_c = \frac{1}{2} \frac{(\Delta I_2) \text{ peak}}{\Delta E_{c_1}} \quad (8)$$

In words, Equation 8 reads:

20 The conversion conductance is equal to one-half the change in peak value of the fundamental component of the output electrode current divided by the change in potential of the signal electrode.

25 The circuit actually embodying the present invention is depicted in Fig. 2. Transformer 3 supplies 60 cycle alternating current to the circuit comprising variable resistor 4, resistor 5 and field coil 6 of a milliammeter of the dynamometer type. It is apparent that current from the secondary 7 of transformer 3 will flow through resistor 5 and field coil 6 and that the potential drop across resistor 5 will necessarily be in phase with the current through field coil 6, since that potential drop will be produced by the flow of current. Oscillator grid 8 of converter tube 9 is connected to such point on resistor 5 as to impress on the grid 8 a voltage substantially the same as will be carried by grid 8 in actual operation. This is determined by measuring the flow of rectified oscillator grid current by means of 30 microammeter 10 in the circuit between oscillator grid 8 and cathode 11. Resistor 12 may be used in the circuit of oscillator grid 8 to effect biasing if desired.

35 Signal grid 13 of tube 9 has applied to it a voltage derived from battery 14 by way of voltage divider 15. Moving coil 16 of the milliammeter is in series with anode 17 of tube 9 and since the plate current is in phase with the oscillator voltage applied to grid 8 and this voltage is in turn in phase with the current through field coil 6, it follows that the currents in field coil 6 and moving coil 16 are in phase with each other. It is to be understood that coils 6 and 16 are mutually coupled magnetically only and 40 that there exists no direct conductive electrical connection between these coils such as to pass conductive current from one to the other. Capacitances 18 provide low impedance paths between the various electrode elements (except grid 60 13) of tube 9 and the cathode at the frequency employed on oscillator grid 8.

The method of measurement is as follows:

A voltage is applied to signal grid 13 by means of voltage divider 15 and the rectified grid current through oscillator grid 8 is brought to the proper value by adjusting the connection of grid 8 to resistor 5. The reading of voltmeter 19 and of the milliammeter having the operating elements field coil 6 and moving coil 16 are taken. The voltage on grid 13 is then varied slightly by an adjustment of voltage divider 15, voltmeter 19 is read, and the value of anode current corresponding to the second voltage on grid 13 is read from the milliammeter. It is then merely a matter of inserting the values of the current and grid voltage increments in Equation 8. 15

The invention herein described and claimed may be used and/or manufactured by or for the Government of the United States of America for governmental purposes without the payment of any royalties thereon or therefor. 20

I claim:

1. The combination with a frequency converter tube having a cathode, an anode and a plurality of grids including a signal grid and an oscillator grid, of means for supplying a low frequency current, current measuring means of the dynamometer type having a field coil and a moving coil electrically conductively isolated from each other and having mutual magnetic coupling only, a resistance and said field coil connected in series with said means, means adjustably connecting said oscillator grid to said resistance to apply a selected voltage to said oscillator grid, means to apply a steady voltage to said signal grid and to vary said voltage in increments, means to measure said steady voltage, means connecting said moving coil in series with said anode, and means constituting low impedance paths at said frequency between said cathode and each of said grids except said signal grid. 40

2. The combination with a vacuum tube having an anode, a cathode and multiple grids, of a current measuring instrument having a fixed and a movable operating element, said elements being operatively associated by mutual inductive coupling only, a series circuit carrying low frequency current and including one of said elements and means to produce a potential difference in phase with the current through said one element, means to apply to one of said grids a selected potential 45 derived from the aforesaid means, means to apply to a second said grid a steady potential selectively variable in increments, means to measure the potential on said second grid, means connecting the other of said two elements in series with said anode, and means constituting low impedance paths at said frequency connecting said cathode to said anode and to each of said grids except said second grid. 55
